ROLLER SKATE

Samuel Segal, Brooklyn, N. Y.

Original application September 14, 1935, Serial No. 40,579. Divided and this application July 23, 1936, Serial No. 92,203

14 Claims. (Cl. 280—11.26)

The present invention relates to skates and more particularly to roller skates of the type having adjustable front and rear shoe supporting plate sections each provided with a pair of roller 5 wheels.

The invention has as one object the provision of an improved roller skate comprising rectilinearly slidable and horizontally swingable complementary jaws for clamping the fore part of a 10 shoe and liftable means for pivotally locking the jaws in a set position.

The invention has an another object the provision of a relatively rugged conveniently adjustable roller skate including plate means for slidable guiding a pair of clamping jaws and a manually liftable plate pivotable relative to the plate means to swingably lock the clamping jaws in a predetermined set position.

The invention has as a further object the provision of a truck removably carrying alined stub shafts and swingable means for interlocking with the stub shaft to prevent lateral displacement thereof.

The invention contemplates as a further object 25 the provision of a swingable truck for supporting alined stub shafts having reduced portions adapted to interlock with spaced sides of a swingable loop retained in removable interlocking relation with the alined shafts by a spring actuated locking member rotatably carried by a fulcrum pin swingably carrying the truck.

The invention comprehends as a further object 30 the provision of a truck swingably mounted on longitudinally disposed fulcrum means having a shoulder cooperating to limit longitudinal displacement of the fulcrum means in one direction, the truck having a swingable loop adapted to removably interlock with reduced portions of the stub shafts to prevent their lateral displacement 35 and means rotatably associated with the fulcrum means adapted to disconnectably retain the swingable loop in an interlocking relation with the stub shafts.

The invention further comprehends the provision 40 of a skate having complementary slidable front and rear plate sections cooperating with an elongated bolt having a swingable manipulator for rotating the bolt to adjust relative displacement of the plate sections, the bolt having locking means for holding the manipulator in alinement therewith or substantially perpendicular thereto, the rear plate section being provided with a bifurcation 45 for removably interlocking or receiving an intermediate portion of the manipulator to prevent transverse displacement thereof.

The invention has as a further object the provision of complementary slidable front and rear shoe supporting plate sections one of which includes an anchoring device for removably gripping a flexible strap against bodily transverse slippage relative to said sections and for rotatably supporting the elongated longitudinally disposed bolt common to the front and rear shoe supporting sections.

Other objects, advantages and features of the invention will appear from the following detailed description when considered in connection with the accompanying drawings which for the purposes of illustration disclose preferred embodiments of the invention in which:

Fig. 1 is a longitudinal view of my skate according to one form of the invention partly shown in section and corresponding wheels at one side of the skate removed from associated trucks.

Fig. 2 is an underneath view of Fig. 1 showing a rear wheel and its stub shaft removed from its truck.

Fig. 3 is a section on the line 3—3 of Fig. 2.

Fig. 4 is an enlarged sectional view on the line 4—4 of Fig. 1.

Fig. 5 is a sectional view on the line 5—5 of Fig. 1, illustrating the strap anchoring device.

Fig. 6 is a perspective view of a swingable clip for interlocking with alined stub shafts to prevent lateral displacement thereof.

Fig. 7 is a plan view of Fig. 1 showing a shoe in dash and dotted lines mounted on the skate.

Fig. 8 is a section on the line 8—8 of Fig. 7.

Fig. 9 is a section on the line 9—9 of Fig. 2.

Fig. 10 is a fragmentary view of the rotatable 35 bolt, common to the front and rear plate sections, partly illustrated in section, and its swingable manipulator disposed in alinement therewith.

Fig. 11 is a view similar to Fig. 1 illustrating another form of the invention.

Fig. 12 is an underneath view of Fig. 11.

Fig. 13 is a section on the line 13—13 of Fig. 12.

Fig. 14 is a section on the line 14—14 of Fig. 12, and

Fig. 15 shows an inverted perspective view of a 45 truck and a wheel disconnected therefrom.

The skate 10 comprises front and rear complementary slidable plate sections 11 and 12 to each of which is secured a channeled shaped member 13 each having spaced depending lugs or ears 14 50 provided with alined openings 15.

Swingably cooperating with each channeled member 13 is a truck generally designated 16 which comprises a yoke 17 having an integral depending hollow bead or knuckle 18 each pro- 55

vided with a pair of spaced slots 19 to form three depending alined hollow curved ears 20, 21 and 22 defining alined bearings for alined stub shafts 23 each of which appropriately carry an anti-frictionally supported roller wheel 24.

Each stub shaft 23 is provided with an annular groove 25 defining a reduced portion 26 and a cylindrical integrally connected boss or enlargement 26' for spacing an adjacent wheel 10 from an outer ear of an associated knuckle and for limiting the insertion of a respective stub shaft therein.

Although a wheel is rotatable relative to its supporting stub shaft, the latter normally is non-rotatably sustained in its knuckle, being prevented from lateral displacement by a swingable clip, broadly denoted 27, which comprises a U shaped member 28 having lugs 29 and 30 extending in opposite directions and integral therewith. 20 Lug 29 is provided with an opening 31 adapted to receive cylindrical shank of stud 32 fixedly secured to inclined wall 33 of an associated knuckle 16. Stud 32 is provided with an enlarged head 34 serving to limit downward displacement of lug 29, there being sufficient clearance between head 34 of the stud and an associated inclined wall 33 to permit slight movement of lug 29 therebetween when the lug or manipulating lip 30 is moved downwardly against the resistance of coiled springs 35 surrounding the spaced headed studs 36 fixedly carried by an associated yoke 17. It will be noted that each U shaped portion 28 is provided with integrally connected spaced extensions 37.

35 With clip 28 closed as illustrated in Fig. 3, spaced extensions 37 are within spaced slots 19 and project into the spaced grooves 25 of the alined pair of stub shafts and accordingly interlock with the latter to prevent lateral or longitudinal displacement thereof.

40 If lip 30 be depressed, its clip 27 tilts or pivots about its beaded stud 32 since the latter is loosely associated with opening 31 and spaced extensions 37 move out of annular grooves 25 of the alined stub shafts. Consequently by grasping a wheel 45 and moving the latter outwardly its stub shaft which is bodily carried therewith may be slidably removed from the knuckle, for example, see Fig. 2, in which a rear stub shaft is shown disconnected from the rear truck.

50 In moving downwardly, lip 30 is guided by the spaced headed studs 36 which are disposed in spaced openings 38, and the lip is resisted against downwardly displacement by helicoidal springs 55 35. Furthermore, by reason of the loose connection between lug 29 with its associated stud 32, clip 27 may be considered as pivoted or swingable relative to its cooperating yoke 17.

With lip 30 depressed, locking extensions 37 60 are clear of the bore defined by its slotted knuckle. Hence a stub shaft may be removed therefrom or a stub shaft may be readily inserted therein. After insertion its associated boss 26' serves as stop means permitting the groove 25 of the stub shaft inserted into the bearing to automatically line up with a slot 19 in the knuckle after which manual pressure is removed from lip 30 and the latter automatically is elevated due to the release of springs 35. Consequently extensions 37 are elevated and enter corresponding grooves 25, interlocking with the walls thereof as previously pointed out to prevent lateral displacement.

70 According to the present invention, a shaft may be conveniently assembled with a truck. The

operator simply depresses lip 30 to swing its clip 27 after which a stub shaft is slidably moved into the knuckle until such movement is resisted by its boss or flange 26'. Lip 30 is manually released and an extension as 37 interlocks with the stub shaft thus inserted.

In the event a ball bearing 40 of a wheel breaks or becomes jammed, they frictionally engage its stub shafts, causing the latter to rotate with its wheel although normally a stub shaft is 10 non-rotatably disposed in the knuckle.

Each yoke 17 of a truck 16 is provided with spaced upstanding lugs 41, each having an opening 42 in registration with opening 15 of an adjacent lug 14 of channel 13, the registered or 15 alined openings 15 and 42 receiving a reduced portion 43 of a fulcrum pin 44 which comprises headed ends 45. In effect each truck is swingably carried by a respective fulcrum pin 44, while the headed ends thereof and its intermediate portion form shoulders 46 and 47 straddling and interlocking with juxtaposed depending and upstanding lugs 14 and 41 of channel 13 and its swingable truck to prevent longitudinal displacement of its fulcrum pin 41, which 25 is straddled by a resilient rubber block 48 for absorbing impacts imparted to the wheels as is well understood.

Referring now to the complementary plate shoe supporting sections, the rear section 12 is 30 provided with an intermediate reduced portion 49 slidably receivable in the transverse slot 50 of the front plate section 11, it being noted, however, (see Fig. 8) that the forward part of reduced portion 49 is guided between sides of the front 35 channeled member 13.

The rear portion 51 of the front plate section 11 is also reduced and is provided with spaced depending longitudinally extending flanges 52 which are slidably guided by the sides of the rear 40 channeled member 13.

Disposed transversely of rear plate section 12 is an irregularly shaped bar or brace 53 having its central portion 54 bent inwardly forming a vertical channel 55 for receiving reduced smooth 45 part 56 of a threaded bolt 57 threadably interconnected with a vertical wall 58 of a strap anchor generally denoted 59 rigidly secured to and depending from the front plate section 11. Brace 53 is provided with offset laterally extending terminals 60 each secured to rear plate section 12 by suitable rivets 61.

55 Swingably carried at the rear end of bolt 57 is a manipulator 62 having a flattened inner end 63 disposed in a bifurcated part 64 of bolt 57 and transversely disposed pin 65 secured to bifurcated part 64 constitutes fulcrum means for pivotally sustaining flattened end 63 of manipulator 62 which may be automatically held in a vertical position by reason of the cylindrical tumbler 66 60 and associated spring 67 confined in an axial bore in bolt 57, that is, manipulator 62 is held in a retained and vertical position. In such position, key 62 is also prevented from transverse displacement relative to the rear section 12. To this 65 end, the latter is provided with a pair of integrally and rearwardly extending spaced lugs 68 defining a slot 69, the walls of which are adapted to interlock or straddle flattened terminal 63 of the manipulator 62.

70 It is apparent that plunger or tumbler 66 cooperates with a vertical face as 68' of flattened terminal 63 and holds or locks the latter in a vertical position substantially perpendicular to the rotatable bolt 17 and if the manipulator is 75

interlocked with the spaced lugs 68, bolt 57 is prevented from accidental rotation.

Where, however, it is desired to rotate bolt 57, manipulator 62 is swung downwardly relative to fulcrum pin 65. During this operation, the retainer or tumbler 66 first moves inwardly until corner 70 is cleared and subsequently moves outwardly and cooperates with rectilinear face 71, thus holding or locking the flattened end or terminal 63 of the manipulator in alignment with bolt 57. When disposed in alignment with the manipulator causes rotation of the bolt and consequently, front plate section 11 may be adjusted relative to rear plate section 12.

15 More particularly, if it is desired to adjust plate sections 11 and 12 to take a large size shoe, the key is disposed in alignment with bolt 57 and the key is turned in one direction, say counterclockwise, hence shoulder 72 abuts the front face 73 of the transverse brace 53 and the front plate section is moved away from the rear plate section. On the other hand, to accommodate a smaller shoe, the bolt may be turned in an opposite direction. In this case, rear shoulder 74 of the 25 bolt abuts rear face 75 of brace 53 and upon rotation of the bolt front plate section moves relatively towards the rear plate section.

The strap anchoring device 59 is provided with spaced arms 76 each constituting a substantially 30 rectangularly shaped lug 77 comprising a depending projection or shoulder 77'. Extending forwardly and horizontally from front wall 58 of the anchoring device is a fork generally designated 78, defining spaced tines or diverging lugs 35 79 forming means frictionally gripping the body of a flexible leather strap 80 threaded into a gap 81 defined by associated tines 79 and depending lugs 77 of the anchoring device. If strap 80 is threaded in the anchoring device as illustrated in 40 Fig. 5, the body of the strap 80 is slightly compressed and frictionally bears against adjacent corners of an associated tine and lug and consequently transverse slippage of the strap is prevented relative to the skate, and the spaced terminal shoulders 77' also cooperate to retain the strap in the anchoring device against displacement longitudinally of the body of the skate.

Although the anchoring device holds the strap against displacement, the latter may be quickly 50 and manually removed therefrom by moving the strap manually and bodily forwardly to clear the spaced tines and depending lugs 77.

According to the invention provision has been made for eliminating the conventional rotatable transversely disposed bolt and its removable key utilized to actuate the transverse bolt in the matter of adjusting complementary jaws disposed at the forward part of the skate for clamping the fore portion of a shoe. In this connection, 60 the herein disclosed skate has its front plate section 11 provided with diverging slots 81, each slidably guiding a cylindrical post 82 fastened to a horizontal arm 83 of a jaw generally designated 84 comprising an upstanding clamping lip 85 adapted to grip the fore part of a shoe mounted 65 on the complementary plate sections 11 and 12.

Each slidably guided post 82 has rigidly secured thereto a collar or flange 86 to prevent removal of its post from a respective guide slot 81. The 70 upper parts of posts 82 cooperate with the several openings or perforations 87 in a flat pivotally arranged locking plate or member broadly indicated 88. It will be observed that openings 87 in the locking plate form two rows of perforations diverging outwardly and in the closed posi-

tion of locking plate 88 the diverging rows of perforations are in registration with adjacent diverging slots 81 in the front complementary plate section 11.

Liftable locking plate 88 is pivotally associated 5 with the front section 11. For this purpose, locking plate 88 includes two depending spaced headed posts 89 extending through slightly enlarged openings 90 in the front plate section 11. About each post 88 is encircled a helicoidal spring 10 91 cooperating with plate section 11 and a head 92 of a respective post to urge the latter downwardly relative to plate section 11, that is, to hold locking plate 88 substantially horizontally and adjacent plate section 11, in other words, in 15 a closed position.

The liftable locking plate 88 has its forward portion 93 overhanging the forward portion 94 of plate section 11. Hence forward portion 93 may be conveniently manipulated or raised relative to plate section 11 as indicated by the dotted lines in Figs. 1 and 11. When lifted, spaced posts 89 are elevated relative to plate section 11 and the rear marginal part 95 of the liftable plate 88 pivots on plate section 11. Also perforations 20 25 87 formerly interlocking with the upper part of the slidable posts 82 are now free of locking plate 88. Hence by grasping a jaw 84, the latter may be slidably moved relatively to plate section 11, that is, its post 82 is guided along an 30 associated biased or inclined slot 81. In other words, when the locking plate is pivotally lifted or opened, the jaws may be moved inwardly or outwardly in respect to plate section 11 and thereafter disposed in an adjusted set position 35 and subsequently manual pressure is removed from the locking plate and the latter closes automatically due to the operation of springs 91 and in the closed position of the locking plate corresponding perforations 87 of the diverging rows 40 45 of perforations receive and interlock with the upper parts of the slidable posts 82, hence preventing rectilinear movement of the spaced jaws 84.

Although jaws 84 are prevented from rectilinear 50 displacement in the closed position of the locking plate, these jaws, however, are rotatably or swingably sustained relative to plate section 11 and the locking plate. This observation may be made by considering Fig. 1, showing the locking plate closed but since posts 82 are rotatably retained in openings 87, that is, displacement of the jaws also causes rotation of their posts relative to diverging slots 81. Consequently, if a 55 shoe 95 shown in dash and dotted lines in Fig. 7 be interposed between the spaced swingable clamps 84, the latter automatically conform to assume a position to grip the fore part of the shoe, provided, of course, the locking plate is closed.

Where it is desired to set the clamps to accommodate a different size of shoe, the operator simply lifts or opens the locking plate and slidably moves the clamps to the required new position after which the locking plate is manually 65 released, thereby closing automatically.

As illustrated in Fig. 7, strap 89 has each of its ends provided with a buckle 96 adapted to interlock with alternate free ends 97 of a flexible leather strap 98 threaded through appropriately slotted spaced heel guards 99 projecting upwardly from the rear plate section 12.

According to the preferred embodiments of the invention illustrated in Figs. 11-15 inclusive, the skate construction is substantially identical to 75.

the form hereinbefore disclosed in detail in connection with Figs. 1-10 inclusive except in the means for swingably supporting a truck and the means associated with the truck to preclude lateral displacement of the removal stub shafts. In this connection, it will be noted, that in Figs. 11-15 inclusive, yoke 17 of a truck is swingably sustained on a fulcrum pin 101 having an annular shoulder 102 cooperating with an upstanding lug 11 to prevent longitudinal displacement of pin 101 in one direction and with a cotter pin key 103 appropriately inserted at the rear or a reduced portion 104 of the fulcrum pin to prevent longitudinal displacement of the latter in another longitudinal direction.

Swingably associated with block 105 secured to yoke 17 is an irregularly shaped one piece loop or clip 109 comprising spaced arms 107 having intermediate portions thereof arcuately depressed to define arches 108 adapted to be arranged in the spaced slots 19 of an associated knuckle 18 and in the spaced grooves 25 of a pair of aligned stub shafts interlocking with the latter to prevent lateral displacement thereof. To removably retain such relation, however, lip 109 of the loop cooperates with a depending tongue 110 of a winged catch 111 rotatably mounted on the fulcrum pin 110, catch 111 being normally urged against an adjacent depending lug 14 of its channel 13 by a helicoidal spring 112 encircling an overhanging headed part of the fulcrum pin 101.

In Figs. 11 and 12 the rear swingable loop is shown open and the front loop is interlocked and retained interlocked. In an open position, tongue 110 of the catch 111 is raised. In a closed position, lip 109 of a loop is interlocked with an associated tongue 110 and the latter is straddled by the spaced arms 107 of the loop (see Fig. 12). In such relation, tongue 110 is in a lowered position and additionally supports lip portion 109 of the loop.

Where it is desired to assemble a pair of aligned shafts in its bearing, catch 111 is manually grasped by its diverging wings 113 and bodily moved against the resistance of its companion spring 112 and rotated to arrange its locking tongue 110 out of alignment with intermediate ear 21 and the pivoted loop is swung out of the bearing. The stub shafts 23 carrying wheels 24 are then inserted into the bearing. When bosses 26 strike the end faces of the bearing, slots 25 of the stub shafts register with spaced slots 19 thereof. Subsequently loop 106 is swung as to dispose its spaced arched portions 108 within grooves 25. The winged catch 111 is then rotated to dispose its interlocking tongue 110 between the terminal of the loop and underneath lip 109 thereof as shown, for example, in Fig. 14. Hence the loop is removably interlocked with tongue 110 of the catch. The action of spring 112 automatically holds rotatable catch 111 against an adjacent lug 14 until manually retracted. It follows therefore that a rotatable catch is retained in an interlocked relation with an associated swingable loop until manually retracted and rotated. To remove a wheel or wheels, the above mentioned steps in the matter of assembling the wheels to its truck, are reversed. In other aspects, both from the standpoint of function and structure, the embodiment illustrated in Figs. 11-15 is substantially identical to the form earlier disclosed in connection with Figs. 1-10.

The present application is a division of appli-

cant's copending application S. N. 40,579, filed September 14, 1935.

In the broader aspects of the invention, I do not desire to be understood as limiting its embodiments to details herein shown illustratively as a wide variety of modifications may be made within the scope of the appended claims without departing from the spirit of the invention.

I claim:

1. In a skate, front and rear slidably guided sections for supporting a shoe, a rotatable bolt extending longitudinally of said sections and carried thereby, a manipulator swingably secured to the rear end of said bolt, spring actuated means for holding said manipulator in alignment with 15 said bolt for rotating the latter and adjustably displace said sections relatively to each other, said spring actuated means adapted to hold said manipulator out of alignment with said bolt, and means for removably receiving said manipulator 20 to prevent transverse displacement thereof.

2. In a skate, front and rear slidably guided plate sections for supporting a shoe, a rotatable bolt extending longitudinally of said sections, a strap anchoring device connected to said front 25 section and rotatably carrying one end of said bolt, brace means connected to said rear section for rotatably guiding said bolt, a swingable manipulator connected to the rear of said bolt, and means adapted to removably interlock with said 30 manipulator to prevent rotation of said bolt.

3. In a skate, front and rear slidably guided plate sections for supporting a shoe, a rotatable bolt extending longitudinally of said sections, an anchoring device depending from said front section and comprising means to frictionally grip a flexible strap to prevent bodily transverse displacement thereof relative to said sections, said anchoring device having means for threadably interconnecting with said bolt, brace means connected to said rear section for rotatably guiding said bolt, a swingable manipulator connected to the rear end of said bolt, spring actuated means 40 cooperating with said manipulator to hold the latter in alignment or out of alignment with said 45 bolt, and means removably receiving a part of said manipulator to prevent rotation of said bolt.

4. The skate according to claim 3 in which a reduced portion of said bolt is rotatably guided in said brace means and constitutes spaced shoulders severally cooperating with said brace means to prevent longitudinal displacement of said bolt during rotation thereof.

5. The skate according to claim 3 in which said anchoring device includes spaced arms and 55 depending lugs having cooperative means to removably grip spaced faces of said strap to prevent bodily longitudinal movement of the latter.

6. The skate according to claim 3 in which said anchoring device includes spaced horizontally disposed diverging arms and vertically arranged depending lugs having cooperative means to removably grip spaced faces of said strap to prevent bodily longitudinal movement of the latter.

7. The skate according to claim 3 further characterized in that said anchoring device comprising horizontally disposed spaced diverging means to removably grip spaced faces of said strap to prevent bodily longitudinal movement of the latter, said rear section having heel portions 70 carrying a flexible strap, and means for interconnecting alternate ends of said strap carried by said anchoring device and said strap associated with said heel portion.

8. In a skate, complementary slidable sections, 75

5 a pair of wheels carried by each section, a bolt extending longitudinally of said sections and operatively associated therewith, swingable key means carried by said bolt, and locking means to hold said key means in alinement with said bolt to permit rotation of the latter or to hold said key means out of said alinement.

9. In a skate, complementary slidable sections for supporting a shoe, a pair of wheels carried by 10 each section, an adjustable bolt extending longitudinally of said sections and operatively associated therewith, swingable key means carried by said bolt, locking means to hold said key means in alinement with said bolt to permit rotation 15 of the latter for adjusting said sections or hold said key means out of said alinement, and means for locking said key means when the latter is out of alinement with said bolt to prevent accidental rotation of the latter.

20 10. In a skate, a shoe support comprising front and rear sections, a bolt disposed longitudinally of said support and sustained by said sections, swingable means connected to said bolt for actuating the latter to adjust said sections, slidable 25 means carried by said bolt, and spring means for holding said slidable means against one part of said swingable means to hold the latter in alinement with said bolt or for holding said slidable means against another part of said bolt to hold 30 30 said swingable means out of alinement with said bolt.

11. In a skate, a shoe support comprising front 25 and rear sections, a threaded bolt disposed longitudinally of said support and rotatably sustained by said sections, swingable means pivotally connected to the rear end of said bolt, movable retaining means carried by said bolt and cooperating with said swingable means to hold the latter in or out of alinement with said bolt, and means carried by said rear section for lock- 35 40

ing said swingable means to prevent rotation of said bolt.

12. In a skate, a shoe support comprising front and rear sections, a threaded bolt disposed longitudinally of said support and rotatably sustained by said sections, means cooperating with said bolt to prevent longitudinal displacement thereof relative to said support during rotation of said bolt, swingable means pivotally connected to said bolt, movable retaining means slidably carried by said bolt and cooperating with said swingable means to hold the latter in or out of alinement with said bolt, and means carried by said rear section for locking said swingable means to prevent rotation of said bolt. 5 10 15

13. In a skate, a shoe support comprising front and rear sections, a threaded bolt disposed longitudinally of said support and rotatably sustained by said sections, fixed means to prevent displacement of said bolt longitudinally of said support during rotation of said bolt, swingable means pivotally connected to the rear end of said bolt, spring means, movable retaining means actuated and carried by said bolt and cooperating with said swingable means to hold the latter 20 25 30 in or out of alinement with said bolt, and means carried by said rear section for locking said swingable means to prevent rotation of said bolt. 35

14. In a skate, a shoe support comprising front and rear sections, a threaded bolt disposed longitudinally of said support and rotatably sustained by said sections, swingable means pivotally connected to the rear end of said bolt, slidable tumbler means carried by said bolt and severally cooperating with parts of said swingable means to hold the latter in or out of alinement with said bolt, and bifurcated means carried by said rear section for locking said swingable means to prevent rotation of said bolt. 30 35

SAMUEL SEGAL. 40
